US0D1031465S

(12) **United States Design Patent** (10) **Patent No.:** **US D1,031,465 S**
(45) **Date of Patent:** **** Jun. 18, 2024**

(54) **WOOD WORKING MITER GAUGE**

(71) Applicant: **Dongguan Hongdui Mechanical Equipment Technology C**, Dongguan (CN)

(72) Inventor: **Yun Hu**, Xianning (CN)

(**) Term: **15 Years**

(21) Appl. No.: **29/800,342**

(22) Filed: **Jul. 20, 2021**

(51) **LOC (14) Cl.** **10-04**

(52) **U.S. Cl.** **D10/65**
USPC **D10/65**

(58) **Field of Classification Search**

USPC D10/61–65, 70–74; D24/140; D18/34.1

CPC B27G 5/023

(57) **CLAIM**

The ornamental design for a woodworking miter gauge, as shown and described.

DESCRIPTION

FIG. 1 is a front view of a woodworking miter gauge according to the invention;
FIG. 2 is a back view of the woodworking miter gauge according to the invention;
FIG. 3 is a right side view of the woodworking miter gauge according to the invention;
FIG. 4 is a left side view of the woodworking miter gauge according to the invention;
FIG. 5 is a top view of the woodworking miter gauge according to the invention;
FIG. 6 is a bottom view of the woodworking miter gauge according to the invention; and,
FIG. 7 is a perspective view of the woodworking miter gauge according to the invention.

1 Claim, 7 Drawing Sheets
